United States Patent Office.

H. M. TEASDALE, OF DANSVILLE, NEW YORK.

Letters Patent No. 80,029, dated July 14, 1868.

IMPROVED COMPOUND FOR ROOFING.

The Schedule referred to in these Letters Patent and making part of the same.

TO ALL WHOM IT MAY CONCERN:

Be it known that I, H. M. TEASDALE, of Dansville, in the county of Livingston, and State of New York, have invented a certain new and useful Compound for Roofing; and I do hereby declare that the following is a full, clear, and exact description thereof, reference being had to the accompanying drawings, and to the letters of reference marked thereon, which form a part of this specification.

The object of my invention is to provide a cheap and substantial compound for covering the roofs of houses, and to this end my composition consists of the following ingredients, when mixed as below described, which are as follows:

I take six (6) gallons of coal-tar, one hundred (100) pounds of sand, twenty (20) pounds of wood or coal-ashes, five (5) pounds of plaster of Paris, two and one-half ($2\frac{1}{2}$) pounds of white lead, and two and one-half ($2\frac{1}{2}$) of salt, to cover a roof consisting of about one hundred square feet. After the mixing of the ingredients above described, I then apply the compound in the ordinary way.

The advantages which I claim in the use of my compound are, first, its imperviousness to moisture; second, its resistance to hot, cold, or damp weather; and, finally, it will not discolor or otherwise damage the rain-water when appropriated for use, and is also fire-proof.

What I claim as new, and desire to secure by Letters Patent, is—

The combination of the within-specified ingredients, when compounded in or about the proportions described, for the purpose set forth.

In testimony that I claim the foregoing as my own, I affix my signature in presence of two witnesses.

H. M. TEASDALE.

Witnesses:

L. B. PROCTOR,
JOHN LITTLES.
